CLAIM

The ornamental design for an incision dressing as shown and described.

DESCRIPTION

FIG. 1 is an upper perspective view of an incision dressing of our new design.

FIG. 2 is a lower perspective thereof.

FIG. 3 is a front view thereof.

FIG. 4 is a rear view thereof.

FIG. 5 is a left side view thereof.

FIG. 6 is a right side view thereof.

FIG. 7 is a top view thereof; and,

FIG. 8 is a bottom view thereof.

1 Claim, 6 Drawing Sheets
